PROCESS FOR RECORDING SOUND RECORDS.

1,421,045.

Specification of Letters Patent. Patented June 27, 1922.

Application filed March 13, 1918. Serial No. 222,226.

To all whom it may concern:

Be it known that I, HENRY L. WADSWORTH, a citizen of the United States, and resident of Lexington, in the county of 5 Middlesex and State of Massachusetts, have invented an Improvement in Processes for Recording Sound Records, of which the following description is a specification.

This invention relates to talking machine 10 records or tablets, and its object is to provide a novel and improved tablet and process of making the same. The invention has particular reference to a record having the laterally cut groove, so called, but is not 15 confined to that type.

In the illustrative drawing of a sound reproducing tablet made according to my 20 novel process, Fig. 1 is a plan, and Fig. 2 a cross-section on the line 2—2 Fig. 1.

20 Heretofore, two methods have been generally used in making record tablets, particularly in forming a record having a laterally undulating record groove. The first and earlier method was to cover the surface of 25 a blank disk, usually of metal or other resistant material, with some so-called non-resisting material, such as lamp-black, that offered no substantial resistance to the action of a recording stylus; then form a 30 shallow original or initial record groove in the non-resisting material by a recording stylus in the usual manner, and finally by the use of an etching fluid, carry this shallow record groove downwardly and into the 35 surface of the disk itself making a permanent or so called matrix record. From this disk a reverse matrix was obtained which, by suitable processes, could be used 40 for reproducing hard, so-called permanent duplicate tablets of the original, in any desired quantities.

This method is unsatisfactory because the etching fluid used on the record tablet is apt to undercut or eat beneath the wall of 45 the groove and thus cause the lateral original cuts of the stylus in the non-resisting material to be inaccurately recorded and reproduced in the tablet of resisting material.

The second method now very generally 50 used, consists in forming the initial or original record groove by the recording stylus in a blank disk entirely of or having a substantial top coating of a so-called semi-resisting or wax-like but non-permanent record receiving substance which

offers some resistance to the travel of the recording stylus, but which will faithfully record the sound wave vibrations if a proper recording point is used. From this a matrix is made by the electro-plating process, which, 60 after being suitably backed and strengthened, can be used as a die for reproducing indefinitely duplicate tablets in any resistance of permanent material used for this 65 purpose.

Both of the before mentioned methods of recording produce originally or initially only temporary or non-permanent records from which permanent master records and duplicates thereof are produced by the processes described. By the first process the 70 initial record groove is not formed in the body portion proper of the disk at all, and except the groove is etched into the disk cannot be reproduced.

The initial record formed by the second process cannot be used for reproducing the sound waves by a stylus without destroying the record unless the reproducing stylus is fed and supported by a feeding device to thus lessen the wear upon the 75 walls of the groove.

I am aware that numerous attempts have been made to convert etched grooves in metal, to which I first above referred, into commercial forms of sound record grooves, by means of a tracing stylus point free to oscillate in accordance with the undulations of such groove, thereby smoothing out the rough places in the walls thereof, in the expectation that the irregularities corresponding to sound waves be not disturbed or modified by such tracing instrument.

This last mentioned process was disclosed 95 relatively early in the development of the phonographic art, and I am also aware that more recent attempts have been made to carry forward this method for improving upon and perfecting the so-called etched 100 record groove, all of which prescribe successive steps that are eliminated by my direct method of forming the completed final groove in the initial sound recording operation.

When I refer herein to the original or initial groove, or to the groove as originally or initially made in metal by my process, I mean to specify a groove completely formed in the initial operation of recording 110

in metal, in contradistinction to the formation of such sound record grooves by successive steps.

It is, of course, well-known that today the 5 type of talking machine most successfully and generally used has no reproducing stylus guiding or feeding means, the record groove alone being relied upon for this purpose. Obviously, for this reason, as well as others, 10 it necessitates the use of a so-called resistant or permanent tablet material that will withstand the action of the needle indefinitely.

The production of record tablets by either 15 of the foregoing described methods is expensive and slow, and for those reasons, and, further, to permit the production and immediate reproduction of original records for use in private or public places of amusement, 20 I have conceived the idea of producing directly and initially an original permanent reproducible record in a tablet of resistant material by scratching the record groove therein, the surface having been first polished 25 and prepared to secure homogeneity and compactness in the material. Such record may be immediately reproduced many times without any auxiliary stylus-feeding or supporting device, the groove acting to guide 30 the stylus. Within the terms "initially" and "original", I intend to include grooves created in the surface of the record blank by the action of a stylus or other groove creating member however it may be oscillated or vibrated, as distinguished from a 35 record groove not created by a stylus or other groove creating member, but by secondary steps such as the etching or molding steps.

40 I have discovered that a substantially permanent record groove may be formed in the highly polished surface of suitable fine grain metal, for example, copper, sheet aluminum, pewter etc., with an ordinary smooth surface faced stylus. For best results the surface of 45 the blank is first properly prepared by filling the voids therein as by the application thereto of an element of wax-like nature which appears to fill the pores or voids between 50 the molecules of material, and thus converts the polished surface into a suitable record-receiving surface. The metals I find best adapted are those which take a smooth and high polish, and which are hard enough so 55 that the stylus, on engaging the tablet, does not readily pass through the surface prepared by the polishing process, into unhomogeneous material beneath, and yet which are not so hard as to prevent an ordinary stylus point from readily scratching or indenting 60 the burnished surface. Obviously an alloy which possesses the proper characteristics can be used equally as well as an unalloyed metal. I find furthermore, that 65 aluminum possesses all of the characteris-

tics necessary to make a record by my process, and I prefer to use this metal. As a filler therefor I prefer to use a film of wax such as paraffin, which acts also as a lubricant for the recording stylus. This lubricating 70 feature I consider an important element of my invention, as it tends to facilitate the vibrations of the needle on the hard tablet surface.

In addition to acting as a lubricant on the 75 surface of the metal, the filler seems to actually enter into the voids and rough spots which exist even in the highly polished metallic surface, and which by means of a microscope may be readily seen. By the combination of polishing and filling an ideal 80 record surface is created.

Within the term "polished" I include any surface which has a smooth finish however produced, and this finish may obviously be 85 imparted by the mechanical process of polishing or it may result from the method of manufacture, as for example, from the treatment in a rolling mill. The effect in either case of such treatment is apparently to break 90 down the crystalline structure of the surface of the tablet, thus producing the necessary homogeneity in the material.

When the record groove is scratched in such a surface, the recording needle in 95 passing through the material is relieved of the necessity of breaking down the crystalline structure of the material.

My novel tablet Fig. 1 may be of any convenient size diametrically and of sufficient 100 thickness to enable the groove to be made therein by the stylus in the making of which the surface of the material is actually scratched or indented as distinguished from bent or deformed. In preparing it I prefer, first, to melt the wax-like material and flow it on to the tablet in the form of a very thin film. I then rub the wax film thoroughly into the surface of the blank either manually or by any suitable device, 110 filling all the voids. I remove all excess material, if any, by rubbing, so that unless critically examined, the presence of the paraffin or wax will not be determined, as the minute quantity of it used is practically invisible.

It is obvious that when I use the expression "surface of the disc" I refer to that particular surface on which the record groove is being formed at the time. Thus it would 120 be practicable as one working method to depress the surface in certain places thereon along a predetermined line or lines, on which I contemplate forming the sound record groove. Such depression might be for various purposes as, for example, to assist in keeping the recording or reproducing stylus to a given line relative to formation of the sound record, but in any such case the original record groove would be made on the 125

polished surface of the disc wherever required.

It is also obvious that in so far as the lubricant herein referred to is used to reduce the 5 friction between the action of the recording stylus and the surface of the disc that such lubricant might be applied in various ways, as for example by having the material itself impregnated therewith previous to the placing 10 of the record groove in the material, or that the stylus or recording member might be the instrumentality by which the lubricant is applied.

Apparently on account of the very fine 15 grain of aluminum, and other characteristics, it is peculiarly adapted to receive and hold in close relation the filler referred to.

The thin film of wax I apply to the metal 20 surface fills these minute apertures or voids, and acts thus to still further smooth or burnish the surface and when subjected to the action of a recording stylus facilitates the formation therein of an accurate groove with smooth, clearly defined walls, both side and 25 bottom.

In the use of a wax filled and polished 30 aluminum surface for recording, no burden of removing or actual cutting out of the material, nor yet of ironing it, as distinguished from the usual incidental pressing of the side walls of the groove, is placed upon the recording stylus. The needle simply scratches or marks the 35 polished, lubricated surface, leaving smooth walled grooves for the guidance of the reproducing needle. The peculiar quality of the metal to receive and record the vibrations of the stylus with unusual accuracy and sharpness and the firm character of the wall created 40 also renders it unnecessary to form so deep a groove as has hitherto been the case with other material; a substantially shallow marking acting to give a clear and otherwise satisfactory reproduction. The shallow 45 groove made does not exceed, ordinarily, the depth to which the effect of the polishing is manifested. That I am able to make a successful phonographic groove in materials so much harder than those heretofore successfully used in the art, I ascribe to the fact that 50 the polishing and preparation of the surface of the tablet creates a homogeneous compression in the material in which the record is to be scratched, and that the condition thus produced prevents the side walls of the 55 groove from being lacerated or torn away on the passage of the stylus point therethrough. The stylus may engage the surface at any angle with either a forward or backward 60 rake, or be run in a position substantially perpendicular to the tablet, and the smooth wall of the groove will be retained. The action of the scratching in each of the positions seems to be substantially the same, but 65 to obviate the successive wear of the stylus

point and to accommodate the needle point more readily to any imperfection in the polished surface, I prefer to point the needle in the direction of rotation.

The action of the stylus on the material 70 is thus shown to be clearly an indenting or scratching thereof as distinct from a cutting or a compressing operation. The materials of a semi-resistant and usually friable character which have heretofore been employed, 75 and in which a deep cut was necessary in order to give a suitable firm-walled sound groove, are so unhomogeneous in character that the groove requires in its making a stylus which will either cleanly remove the 80 material by cutting it out or else a stylus which will compress the side walls, with perhaps some lateral or upward displacement of the material, and also iron out the unhomogeneous condition. With my process neither 85 of the foregoing actions is necessary. The character of the material used makes it possible, for an ordinary stylus, to scratch or indent a smooth walled groove, although were the same stylus used in friable material or in the semi-resistant materials in 90 general heretofore used, the action would be a gouging of the material which would produce more or less unsatisfactory results owing to the cellular and unhomogeneous construction of the material. 95

While I have not yet been able to discover to my entire satisfaction exactly how the wax-like element affects the tablet, apparently it is as hereinbefore indicated. 100

The wax also seems to act, in addition to perfecting the surface of the metal tablet for recording and lubricating the path of the stylus, to absorb the metallic quality of the reproduced tone, and enhance its purity 105 and volume. It also appears to act to a sufficient degree as a guide for the reproducing stylus, which, in a shallow groove would otherwise have a tendency to jump out. Although the wax filler is almost too 110 negligible a quantity to be seen, experiments have proven to my satisfaction that it does act to help guide the reproducing needle. I have obtained the best results when a light rather than a heavy wax is used, and have 115 found that oil or other lubricant or filler may be used with similar, but not so satisfactory results.

In my use of the term "wax" and "oil" 120 wherever they may occur, I use them synonymously so far as the general purposes of their employment in this invention are concerned. By these terms I intend to include any element which from its consistency may be a 125 filler or lubricant, or serve the purpose of a filler or lubricant, that is, to eliminate the friction between the stylus point and the tablet surface.

A tablet made according to the foregoing 130 method is sufficiently permanent to permit it

to be reproduced instantly and many times, and to permit the groove to act as a feeding means for the reproducing stylus.

Such a tablet is inexpensive to make, requiring no master record or matrix, is non-breakable, may be quickly produced, and is especially adapted for use also as a ready means of communication, as one may record a message thereon and safely mail it to another, to be readily reproduced. No substantial expense is entailed in making the record itself, as the tablet prepared for use may be readily manufactured and sold commercially at a reasonable price, and an ordinary reproducing stylus will make a very satisfactory record.

Obviously, if when reproducing, a needle somewhat less hard than the tablet is used, the life of the record is prolonged. Certain semi-resisting materials have heretofore been used for tablets which, after hardening, either naturally, during a certain period of time, or by the application of chemicals thereto, or by other artificial methods, have been sufficiently hard or resistant to withstand reproduction a few times on the type of machine having an unfed stylus. But these tablets are not adapted for instantaneous reproduction, and in many cases the processes of treatment and manufacture are very complicated.

While I have described one embodiment of my invention and one method of making the same, obviously my invention is not limited in its details to the particular disclosures here made.

Claims.

1. An original record tablet comprising a metallic base with a wax-like film thereon, and a reproducible record groove scratched in the metal.

2. A tablet comprising a metallic base having its voids wax filled and adapted to receive an original sound record thereon.

45 3. An original record tablet comprising a metallic base, a wax-like film thereon, and a stylus feeding sound reproducing groove.

4. A tablet comprising a void filled aluminum base, and adapted to receive an 50 original sound record thereon.

5. A record tablet having a base of resistant material with a void filled surface, and a record groove scratched initially therein.

55 6. The process of making a sound record in a tablet of resistant material and capable of instantaneous reproduction, comprising filling the pores or voids of the material with a wax-like substance to perfect the surface, and then forming a record groove therein.

7. The process of making an original sound record in resistant material comprising first, burnishing or polishing the 60 surface of the material and subsequently mark-

ing or scratching the record therein without removing an appreciable amount of material.

8. A tablet of aluminum having a sound record groove marked or scratched therein, 70 the surface of the tablet having its crystalline structure polished and broken down.

9. A tablet of metal having a reproducible original record groove formed therein.

10. A tablet of aluminum having a stylus- 75 guiding original record groove formed initially and directly therein.

11. A tablet of resistant material having a lubricated surface with a reproducible record groove formed initially therein.

12. A tablet of metal having a lubricant filled surface with an original record groove formed initially thereon.

13. A tablet of aluminum having a wax or oil filled surface with a record groove 85 formed initially thereon.

14. A phonographic tablet of metal having a burnished surface with a sound groove marked or engraved initially thereon capable of being reproduced without further treatment.

15. The process of forming an original record groove in a tablet of resistant material which consists in filling the surface voids with a wax-like material, and marking 95 or scratching the phonograph record groove initially thereon.

16. The process of forming an original record groove in a tablet of metal which consists in filling the surface voids with a 100 wax-like material, and marking or scratching the phonograph record groove originally thereon.

17. The process of forming an original record groove in a tablet of aluminum which 105 consists in filling the surface voids with a wax-like material, and directly marking or scratching an original and reproducible phonograph record groove thereon.

18. The process of forming an original 110 record groove in a tablet of metal which consists in lubricating the surface on which the recording stylus point is to run with an oily or wax-like substance and marking or scratching a reproducible record groove directly thereon.

19. A record tablet of resistant material having a polished homogeneous surface with an original reproducible record groove 115 therein.

20. A record tablet of resistant material having a polished homogeneous surface with its voids wax filled and having an original reproducible record groove.

21. The process of forming a phonographic record which consists in polishing the surface of a tablet of resistant material, and scratching a reproducible record groove 125 therein.

22. The process of forming a phono- 130

graphic record which consists in polishing the surface of a tablet of metal, filling the voids therein with a wax-like material and scratching a reproducible, sound groove 5 therein.

23. The process of forming a phonographic record which consists in treating the surface of a tablet of metal with a lubricating and void filling material, and scratching 10 a laterally oscillating record groove therein.

24. A tablet of metal having a lubricated surface with an original reproducible record groove formed initially therein.

25. A record blank of polished resistant 15 material having its surface voids lubricant filled.

26. A record tablet blank of polished aluminum, having its surface voids lubricant filled.

27. An original record tablet comprising 20 a metallic base with a recording surface, the crystalline structure of which has been broken down, and having the record sound groove scratched or otherwise formed in the metal.

28. A record tablet comprising a polished, 25 film covered metallic base with an original reproducible record therein, the crystalline structure of the tablet being broken down 30 on the recording surface.

29. The process of forming a phonographic record which consists in breaking

down the crystalline structure of the surface of a tablet of resistant material, and scratching a reproducible record groove thereon. 35

30. The process of forming an original phonographic record which comprises producing movement of a self-supporting ductile metal blank and forming a sound record 40 groove therein by a stylus pressing against the surface of the blank.

31. The process of forming an original phonographic record which comprises producing movement of a self-supporting ductile metal blank and forming a sound record 45 groove therein by a stylus pressing at its point against the surface of the blank.

32. The process of forming an original phonographic record which comprises producing movement of a self-supporting ductile metal blank and forming a laterally undulating record groove therein by a stylus 50 pressing against the surface of the blank.

33. The process of forming an original phonographic record which comprises producing movement of a self-supporting ductile metal blank and forming a laterally undulatory record groove therein by a stylus 55 pressing at its point against the surface of the blank. 60

In testimony whereof, I have signed my name to this specification.

HENRY L. WADSWORTH.
